UNITED STATES PATENT OFFICE.

LIONEL B. BERESFORD, OF BEVERLY, NEW JERSEY.

GAME.

Application filed November 18, 1920. Serial No. 423,974.

To all whom it may concern:

Be it known that I, LIONEL B. BERESFORD, a citizen of the United States, residing at Beverly, in the county of Burlington and State of New Jersey, have invented certain new and useful Improvements in Games, of which the following is a specification.

This invention relates to games the object of which is to provide a game simulating a battle field which is not only amusing but likewise educational. The device is especially useful in teaching children the art of warfare and impressing upon them the necessity of thought before action.

Another object of the invention is to provide a simple and inexpensive game apparatus which is fashioned after standard types of games and played in a manner similar to other board games.

The above and other objects of this invention will be in part described and in part understood from the following description of the present preferred embodiment of the invention taken in connection with the accompanying drawings, wherein:

Fig. 1, is a plan view of a board constructed in accordance with my invention showing the game pieces thereon.

Fig. 2, is a perspective view of one of the game pieces known as one of the privates or men, and

Fig. 3, is a perspective view of one of the game pieces known as officers.

The game board shown in the drawings is indicated at 4 and is preferably of a rectangular configuration. One face of the board is provided with a plurality of white squared faces 5 and black squared faces 6 constituting blocks which are inscribed on the entire face of the board from one margin thereof to the other. Certain rows of these blocks are segregated by a line 7 which latter constitutes a battle line. These segregated blocks constitute the portion of the field held by one side, which will hereinafter be referred to as A. A second battle line, such as that indicated at 8 segregates another series of blocks which represents the territory held by the other side, this being indicated at B. The portion of the board between the battle lines 7 and 8 constitutes "no man's land" and is indicated at C.

Each side A and B has a plurality of game pieces hereinafter referred to as men 9, which in this instance are shown to

be of a circular configuration and are engageable with the blocks 6 of the board within their own battle line. Also each side is equipped with a plurality of game pieces hereinafter referred to as officers 10, which are likewise preferably of circular configuration, and, if desired, may be larger in size than the game pieces constituting the men. The officers are numbered and are engageable with correspondingly numbered blocks 6 behind their own battle lines from which points they start in initiating a game.

A goal 11 or fort is arranged behind the battle line 7 and a goal or fort 12 arranged behind the battle line 8, each of which constitutes five blocks arranged in the form of a Maltese cross. These goals are preferably arranged midway the sides of the game board so as to make entry thereinto difficult, thereby increasing the interest in the game.

In playing the game the men 9 and officers 10 are arranged as shown in Fig. 1 of the drawings. Each player starts off by moving one officer and one man. The officers may be moved in any block desired, but the men can be moved only from one black block 6 to the other behind his own battle line and in "no man's land." However, as soon as one of the men 9 gets behind the battle line of the enemy he is permitted to travel over any one of the blocks in order to gain entrance to the goal of the enemy. The men and officers are jumped during the playing of the game the same as in checkers. As soon as one of the game pieces representing a man is jumped it is removed permanently from the board. However, when an officer is jumped he is placed back on the board at the block where he started from. Any desired number of points may constitute the game, and any desired number of points may be allowed for each man or officer which enters the goal of the enemy. It is customary however to allow ten points for each man and fifteen points for each officer which enters the goal of the enemy.

Although I have above described what constitutes the preferred manner of playing this game, it is nevertheless to be understood that the game may be modified as desired or different games may be played on the board without departing from the spirit of the invention. Moreover, the size and configuration of the game pieces may be

changed to satisfy the caprice of the manufacturer. In playing the game it is preferred that different colored game pieces be used, that is, a certain color for one side and 5 a certain color for the other side so that confusion will not exist in playing the game.

What is claimed is:

1. A game board including a checkered surface divided into three parts constituting 10 two battle lines and an intermediate portion constituting a "no man's land", game pieces mounted upon the board behind each battle line and movable into "no man's land" towards the opposite battle line, and 15 a goal of Maltese cross configuration arranged behind each of said battle lines for the reception of game pieces which successfully traverse the board through "no man's land" and behind the enemy battle line.

2. A game including a board having a 20 checkered surface and equipped with game pieces, some of which constitute men and others officers, said officers being movable through any of the blocks of said checkered surface and said men being movable only 25 through one type of blocks constituting the surface, and a goal of Maltese cross configuration arranged on the checkered surface midway between the margins of the board to receive the men and players which successfully traverse the board. 30

In testimony whereof I affix my signature in presence of two witnesses.

LIONEL B. BERESFORD.
